[57] CLAIM

The ornamental design for an inflatable neck pillow, as shown.

DESCRIPTION

FIG. 1 is a top plan view of an inflatable neck pillow showing my new design;

FIG. 2 is a left side elevational view thereof;

FIG. 3 is a front elevational view thereof;

FIG. 4 is a rear elevational view thereof;

FIG. 5 is a right side elevational view thereof;

FIG. 6 is a bottom plan view thereof; and

FIG. 7 is a front, top and left side perspective view thereof.

The broken-line depiction of the valve stem is shown for illustrative purposes only and forms no part of the claimed design.

FIG.1

FIG.2

FIG.3

FIG.5

FIG.6

FIG. 7
